UNITED STATES PATENT OFFICE.

GARFIELD J. EDMONDS, OF PHILADELPHIA, PENNSYLVANIA.

GARMENT PRESSER.

Application filed April 4, 1922. Serial No. 549,515.

To all whom it may concern:

Be it known that I, GARFIELD J. EDMONDS, a citizen of the United States, residing at Philadelphia, in the county of Philadelphia and State of Pennsylvania, have invented 5 new and useful Improvements in Garment Pressers, of which the following is a specification.

This invention relates to garment pressers and it has more particular reference to devices of the kind which are intended to be clamped on folded or creased garments to press the same. More specifically this invention has reference to what may be termed a combination supporting and creasing device for effecting the pressing of trousers and the like.

Another object of this invention is to provide a device of the foregoing character 20 with which is combined a means that may be moistened with water prior to inserting said means between the two portions of a folded garment, more particularly men's trousers, so as to impart moisture to the 25 cloth which is intended to be creased, whilst being supported or held supported either by the longitudinal edges of each trouser leg or alternatively by the cuffs at the bottom thereof.

30 A further object of this invention is to provide a novel device of the character hereinbefore described with which is associated a cuff creasing means, said means being of a nature to crease the cuff portions of a pair 35 of trousers, whilst allowing the trousers to be suspended thereby in a vertical position.

A still further object of this invention is 40 the provision of a device of the foregoing character which is so constructed that any ordinary style or size of trousers may be pressed thereby.

Other objects reside in the provision of a combination garment presser and hanger which is simple in construction, inexpensive 45 to manufacture, highly efficient in use and with all a general improvement in the art to which this invention relates.

With the foregoing and other objects in view as will be more apparent from the 50 following description, my invention consists essentially in certain novel features of construction, combinations and arrangements of parts hereinafter fully described and more specifically defined by the appended claims.

55 In the further disclosure of the invention

reference is to be had to the accompanying sheet of drawings constituting a part of this specification and in which like characters of reference designate the same or corresponding parts in all the views.

Figure 1 is a side view in elevation illustrative of one practical embodiment and application of my invention, the same being shown in associated relation with a pair of trousers, the latter being indicated in 65 dotted outline.

Figure 2 is a transverse section on the line 2-2 in the preceding figure and drawn to an enlarged scale for a better understanding 70 of its component parts.

Figure 3 is a fragmentary top plan view of one of the clamping members; and,

Figure 4 is a side view partly broken away 75 and in section of that part of the invention which is particularly adapted for pressing and creasing the cuffs of a pair of trousers.

Referring more particularly to the views the numerals 10 and 11 designate longitudinal clamping members or leaves which are hingedly connected together by means 80 of hinged plates 12, 13, appropriately secured to the clamping members or leaves by means of wood screws or the like 14. A central dividing member or loose leaf is designed by the numeral 15, said separating 85 leaf being adapted in use to divide the folded edges 16, 16 of the material to be pressed, such as the legs of a pair of trousers. It is to be particularly noted at 90 this point that the separating leaf 15 is in no way connected to the device but is intended to serve as a moisture imparting element, and to this end it should first be moistened or dampened with water prior to insertion between the aforesaid legs 16, 16 of 95 a pair of trousers.

A clamping member or hinged plate 12 is fitted with a screw bolt 17 hingedly pivoted thereto at 17' and the movement thereof being limited by stops 18, the aforesaid screw bolt 17 being adapted to extend through and beyond the clamping plate or other hinged member 13; said screw bolt 17 being also provided with a wing-nut 19 for exerting 100 the necessary pressure to effect the proper 105 creasing of the trouser legs. The upper portion of the clamping plate 13 is formed or fashioned with a rectangular aperture 20 through which the tongue 20' provided at the extreme end of the L-shaped portion 12' 110

of the clamping plate 12 passes and is rolled over to constitute a substantial hinged connection.

In the upper portion of the clamping plate 13 directly below the aperture 20 I provide or form what may be termed a key-hole slot 21, said key-hole slot providing a simple means whereby the wing-nut 19 may be passed therethrough when pressure is removed and the screw bolt 17 and wing-nut 19 are in the position as indicated by the dotted lines in Figure 2; said means providing for the easy and quick opening of the device in the direction indicated by the arrow shown on the above referred to figure. In order to provide a simple device which is adapted for clamping attachment to the cuff portions of a pair of trousers, it will be obvious that I will employ an abbreviated section, such as is shown in Figure 4 to an enlarged scale, said section including the clamping members or leaves 10, 11 and interposed section or leaf 15 in the same manner as hereinbefore described. With the exception that the central dividing member 15 is made in two sections 22, 23, the object being to eliminate pressure on that part of the cuff, namely, the center portion where the seam in the trouser leg occurs, and also to provide a simple means for hanging therebetween a bail or handle 24 whereby the device may be supported or hung in a vertical position. The aforesaid bail or handle 24 has its two ends 25, 26 appropriately bent at right angles and securely fitted in apertures 27, 28 provided for their reception in the aforesaid dividing sections 22, 23.

In order to provide a simple means whereby the device may be suspended as shown in Figure 1, I preferably provide a hook 28 for connection into a staple or other supporting means 30 provided for the purpose in a wooden batten 31 or other appropriate piece of furniture, wall or the like, where it is desired and convenient to support the device.

Obviously two such sections *a* and *b* are employed, the one being adapted to crease the front and the other the back of a pair of trousers as shown in dotted outline at *c*.

From the foregoing description and examination of the drawings the numerous advantages and simple nature of my improved garment presser will be self-evident and it will be perfectly obvious that the interposed leaf 15 may be covered on its longitudinal faces with felt or other appropriate moisture retaining material, but I have found in actual practice that such covering is not essential.

While I have shown and described a preferred embodiment of my invention it is to be clearly understood that the same is susceptible of detailed changes as well as variation in the shape and pattern of the several

co-related parts, and the right is hereby reserved to make such changes, variations and other combinations as fairly lie within the scope of the appended claims.

Having described my invention, what I claim as new and desire to secure by Letters Patent is:

1. A garment pressing device including a pair of elongated leaves between which the portions of the garment to be creased are placed, a separating leaf of like configuration for interposition between the folds of material during the creasing operation, means hinging the elongated leaves together, said means including substantially L-shaped members secured to one of the elongated leaves and having tongues engaging in the slotted upper ends of slightly bent members secured to the opposed elongated leaf, means for clamping the elongated and interposed leaves firmly together in operative position, and means whereby the device may be suspended in a pendant position.

2. A garment pressing device including a pair of elongated leaves between which the portions of the garment to be creased are placed, a separating leaf of like configuration for interposition between the folds of material during the creasing operation, means hinging the elongated leaves together, said means including substantially L-shaped members secured to one of the elongated leaves and having tongues engaging in the slotted upper ends of slightly bent members secured to the opposed elongated leaf, means for clamping the elongated and interposed leaves firmly together in operative position, and means including screw bolts having T-heads engaging in loops stamped out from the aforesaid L-shaped members, and wing-nuts for clamping engagement on the opposed slightly bent members, and means whereby the device may be suspended in a pendant position.

3. A garment pressing device including a pair of elongated leaves between which the portions of the garment to be creased are placed, a separating leaf of like configuration for interposition between the folds of material during the creasing operation, means hinging the elongated leaves together, said means including substantially L-shaped members secured to one of the elongated leaves and having tongues engaging in the slotted upper ends of slightly bent members secured to the opposed elongated leaf, means for clamping the elongated and interposed leaves firmly together in operative position, said means including screw bolts having T-heads engaging in loops stamped out from the aforesaid L-shaped members, wing-nuts for clamping engagement on the opposed slightly bent members, said slightly bent members having key-hole slots therein for the passage of the wing-nuts to effect the

quick release of the device, and means whereby the device may be suspended in a pendant position.

4. A garment pressing device including a pair of elongated leaves between which the portions of the garment to be creased are placed, a separating leaf of like configuration for interposition between the folds of material during the creasing operation, means hinging the elongated leaves together, said means including substantially L-shaped members secured to one of the elongated leaves and having tongues engaging in the slotted upper ends of slightly bent members secured to the opposed elongated leaf, means for clamping the elongated and interposed leaves firmly together in operative position, said means including screw bolts having T-heads engaging in loops stamped out from the aforesaid L-shaped members, wing-nuts for clamping engagement on the opposed slightly bent members, said slightly bent members having key-hole slots therein for the passage of the wing-nuts to effect the quick release of the device, means for limit-

ing the movement of the aforesaid screw bolts, and means whereby the device may be suspended in a pendant position.

5: A trouser presser comprising a plurality of pairs of elongated leaves between which the front and back portions of the trousers to be creased are placed, separating leaves of like configuration interposed between the folded edges of the legs of the trousers during the creasing operation, means hinging the aligning pairs of elongated leaves together, means for clamping the elongated and interposed registering leaves firmly in operative position, means whereby the device may be suspended in a pendant position, and an auxiliary set of leaves of similar nature for effecting the pressing of the cuff portions at the bottom of a pair of trousers, the interposed leaf in the auxiliary set including opposed portions between which is pivoted a bail whereby the trousers may be suspended bottom upwards in a pendant position.

In testimony whereof I affix my signature.
GARFIELD J. EDMONDS.
